ANTENNA ROTATOR CONTROL HOUSING

Fred L. Toerge and Marvin E. Garfinkle, Stamford, Conn., assignors to Cornell-Dubilier Electric Corporation, a corporation of Delaware

Filed July 5, 1968, Ser. No. 12,640

Term of patent 14 years

Int. Cl. D10—11

U.S. Cl. D52—6

FIG. 1

FIG. 2

FIG. 3

FIG. 4

FIG. 5

FIG. 6

FIG. 1 is a perspective view of an antenna rotator control housing made in accordance with this invention;

FIG. 2 is a front elevational view of the housing;

FIG. 3 is a top plan view of the housing;

FIG. 4 is a bottom plan view of the housing;

FIG. 5 is a side elevational view of the housing; and

FIG. 6 is a rear elevational view of the housing.

The dominant features of the invention reside in those portions of the drawing shown by means of full lines.

We claim:

The ornamental design for an antenna rotator control housing, as shown and described.
